UNITED STATES PATENT OFFICE.

RALPH E. STUART, OF BUFFALO, NEW YORK, ASSIGNOR TO KNIFFIN & DEMAREST CO.,
A CORPORATION OF NEW YORK.

DESIGN FOR CROCKERY AND CHINAWARE.

59,039.

Specification for Design.

Patented Sept. 13, 1921.

Application filed May 12, 1921. Serial No. 469,052. Term of patent 14 years.

To all whom it may concern:

Be it known that I, RALPH E. STUART, a citizen of the United States, residing at Buffalo, in the county of Erie and State of New York, have invented a new, original, and ornamental Design for Crockery and Chinaware, of which the following is a specification, reference being had to the accompanying drawing, forming part thereof.

The figure is a view of a plate with my new design applied to a part thereof.

I claim:

The ornamental design for crockery and chinaware, as shown.

RALPH E. STUART.
